UNITED STATES PATENT OFFICE.

PAUL GOEBELS, OF DESSAU, GERMANY.

DRUM MILL.

Application filed March 9, 1927, Serial No. 174,038, and in Germany September 3, 1926.

Mills are known in which the grinding space is subdivided by longitudinal partition walls. In mills of this kind the material to be ground passes through the chambers formed by said walls in one and the same direction. If there are, for instance, three grinding spaces in the drum the material is subdivided into three portions which pass in parallel directions from the supply end of the drum to the delivery end of the same. Drums of this type must be relatively long in order to warrant obtaining a certain fineness of the ground material at the delivery end of the drum, and they are, therefore, heavy, expensive and require much power.

The present invention obviates these drawbacks. It relates to an improved design of drum mills. These improved mills are only short, comparatively light and cheap, and require by far less power than the aforementioned mills. The invention is illustrated diagrammatically and by way of example on the accompanying drawing on which Figure 1 is an axial section through a drum mill designed according to this invention, and Figure 2 a cross-section through the same.

The constructional form shown as an example is a drum mill, the grinding space of which is subdivided by three longitudinal radial partition walls *a a a* into three grinding chambers or compartments *b c d*. There are also two frontal chambers *f h* on the one side and *g i* on the other side of grinding chambers *b c d*. Intermediate the chambers or compartments *f* and *i* as well as intermediate the chambers *g i* are provided oblique walls as shown in Fig. 1 of the drawing. The grinding chamber *b* communicates with the compartments *f* and *g*, the grinding chamber *c* with the compartments *g* and *h*, and the grinding chamber *c* with the compartments *h* and *i*.

The material to be ground enters through the central sleeve *e*, and passes through the drum by way of the compartment *f*, grinding chamber *b*, compartment *g*, grinding chamber *c*, compartment *h*, grinding chamber *d*, compartment *i* and outlet sleeve *k*, as indicated by the arrows in Fig. 1.

Of the two frontal walls at either end of the drum, the inner walls are provided with apertures 1 for the passage of the material as shown in Fig. 2.

These apertures are so arranged that the longitudinal chambers *a b c* of the drum will

be connected in such a manner that the material will pass through the chambers *a b c* and the chambers *f h* and *g i* in the above indicated succession.

While I have shown in the drawing a constructional form in which the drum is subdivided into three grinding chambers, I wish it to be understood that a grinding drum designed according to this invention may be subdivided into less than three or more than three chambers, that is to say, two or four or even more. It does not matter whether the charging sleeve and the delivery sleeve are located on different ends of the drum or on the same end. In the case of an odd number of grinding chambers the two sleeves will be located at different ends of the drum, as in Fig. 1, and in the case of an even number of chambers they will be located at the same end co-axially.

Whatever number of grinding chambers may be chosen, the total length of the grinding path is constituted in every case by all chambers of the drum mill, so that the total grinding length can be twice or thrice or four times etc. that of the length of the drum itself. This is what the invention has aimed at, and attained.

I claim:

1. A drum for mills comprising a plurality of chambers arranged parallelly to each other in longitudinal direction within said drum, a plurality of chambers arranged at either end of said drum, and apertures between said former chambers and said latter chambers, whereby said chambers will all be connected in succession to each other.

2. A drum for mills comprising a plurality of longitudinally arranged partition walls subdividing the drum into a plurality of parallel chambers, a plurality of frontal chambers provided at either end of said drum, and passages between said frontal chambers and said longitudinal chambers,

said passages being adapted to connect all of said chambers in succession, whereby the material which is supplied to the mill will be forced to pass from one of said frontal chambers into one of said longitudinal chambers, from here into the second of said longitudinal chambers, and from here to the second of said longitudinal chambers and so forth, substantially as described and for the purposes set forth.

In testimony whereof I affix my signature.

PAUL GOEBELS.
